UNITED STATES PATENT OFFICE.

ADDISON BRADFORD, OF BROOKLYN, NEW YORK; WM. W. BLACKMAN, ADMINISTRATOR OF SAID ADDISON BRADFORD, DECEASED, ASSIGNOR OF FIVE-SIXTEENTHS TO THEODORE C. WIGGINS, OF SAME PLACE, AARON R. SMITH, OF NEW BRIGHTON, AND ALBERT S. COMSTOCK, OF NEW YORK, N. Y.

LUBRICATOR.

SPECIFICATION forming part of Letters Patent No. 293,706, dated February 19, 1884.

Application filed July 25, 1883. (No model.)

To all whom it may concern:

Be it known that I, ADDISON BRADFORD, of Brooklyn, in the county of Kings and State of New York, have invented certain new and useful Improvements in Lubricators; and I do hereby declare that the following is a full, clear, and exact description of the invention, which will enable others skilled in the art to which it appertains to make and use the same, reference being had to the accompanying drawings, and to the letters of reference marked thereon, which form part of this specification.

This invention relates to lubricators for car-
15 axle journals and the like, and has for its ob-
ject the economical supplying of lubricant to
the axle, by means of rollers or equivalent
means, in suitable quantities, without, however,
having the rollers themselves in contact with
20 the body of the oil in the box, and also to pre-
vent the waste of oil from the rear of the axle.

The invention consists in providing a suit-
able frame-work to rest upon the bottom of the
journal-box of the axle or other journal, and
25 having connected thereto lubricating-rollers
suspended under the journals, and kept in con-
tact therewith by means of springs, and in
other details of construction, as will hereinaf-
ter appear.

Referring to the drawings hereto annexed,
30 Figure 1 represents a perspective and plan
view, and in elevation clearly showing all the
working parts, but detached from the journal-
box. Fig. 2 is an end elevation, showing the
oil-supply devices in two positions. Fig. 3 is
35 an edge view of the oil-supply springs, and
Fig. 4 illustrates a modification in which the
eccentrics are dispensed with.

A is the frame, which may be made of any
suitable form and material. Secured to this
40 frame are two flat springs, B, suitably formed
in such manner that by their tension they sus-
tain the oilers in contact with the journal.

Across the base-frame A, I construct what I
term a "cross-head" or "frame," C, having
45 two sides, and carrying a pair of rollers or oil-
ers, D, mounted therein in suitable bearings,
and adapted to revolve by the motion imparted
to them by the rotary action of the journal.

Upon these rollers D are secured on each a
pair of cams or eccentrics, a a, which operate 50
a pair of side levers or yokes, b b, which have
on their upper end an inwardly-projecting
bearing, c c, that works on the face of the ec-
centrics in such manner that an up-and-down
movement is imparted to them when the oil- 55
rollers revolve. These yokes work up and
down in guide-slides d d, which are secured to
the cross-head C. The lower ends of the yokes
are secured together by tie-rods or small
shafts e e, which carry small wheels or rollers 60
f. These small rollers are adapted to be sub-
merged in the lubricating-oil, and when the
eccentrics rise up they carry these small roll-
ers f with them, bringing them in contact
with the large rollers, to which they impart 65
the oil adhering to them. In this way a suffi-
cient quantity of oil is supplied to the jour-
nals and bearings without wasting the oil, and
without constantly agitating it, by which it
becomes gummy and sticky, rendering it unfit 70
for use.

Upon the inner ends of the frame A, I lo-
cate on each end a spring rubber or wiper, E,
which may be secured by the same bolt as
spring B, or by other suitable means. These 75
spring-wipers are for the purpose of wiping
off the surplus oil of the rear end of the jour-
nal, whereby its waste is prevented. The
spring-wipers maintain themselves in contact
with the journals by their own resiliency, and 80
are therefore, like all the working portions
of lubricator, automatic in action, all of
which will be more fully hereinafter explained
by further referring to the drawings here-
unto annexed. These journaled wheels or 85
rollers, with cams on their sides, are for the
purpose, as they revolve, of raising the drop-
pieces connected with the frame-work, the
lower ends of which fall into the lubricant, as
the shorter side of the cam is uppermost. 90
When the longer side of the cam goes up, it
raises the drop, bringing the small roller in
the lower end of the drop in connection with
the rollers of the lubricator that bear against
the axle-journal, supplying at each time a 95
small quantity of oil, that is taken off by the

revolving lubricator-rollers; and is thus applied to the axle-journal. By causing a greater or less contact-point to the feeders the quantity of oil supplied is regulated. The contact-point of the feed may be of yielding substances, if desired; also, the contact part of the roller may be of any yielding substance.

A suitable frame-work, to rest on the bottom of the journal-box, has attached to it springs fastened at one end, the other end rising, so as to connect with the frame-work in which the rollers are journaled to hold them, the said rollers bearing contact with the axle-journal. The springs thus adjust the rollers to the condition of the box and journal. To this frame-work, resting on the bottom of the journal-box, are also attached springs and contact-bearing ends to take off the surplus oil at the rear of the bearings.

At Fig. 3 will be seen a wire connected to the frame-work, which may be loosely bent around a small rod, one end operating against the cam of the roller. The other, by gravity or tension, goes down into the oil and up against the other roller as actuated by the cam movement of the cam-roller. Fig. 4 shows the feed-wire bent so as to feed the oil to the roller that gives it its action; also, that one wheel or roller may be used, instead of a greater number, to do the lubricating, and that instead of a cam there may be a projecting pin on the side of the wheel. Said pin may have a loose roller on it to reduce friction, or the wheel might be grooved to operate the feeder.

The roller or wheels, with their frame-work and bearings, as represented in Figs. 1 and 2, may be applied to the frame with raised springs, as represented in Fig. 4. It is evident that said roller or rollers may operate the feeders, so as to apply the oil direct to the journal.

Having described simple forms of my lubri-

cator, it is readily seen that there may be modifications of construction within wide scope of my invention; therefore I do not restrict myself to the forms described. 45

What I claim as new, and desire to secure by Letters Patent, is—

1. A lubricator having the base-frame adapted to rest on the bottom of the journal-box, 50 and having springs secured thereto, which are adapted to sustain a lubricating device, which device is kept in contact by the resiliency of said springs, substantially as described.

2. The combination, in a lubricator, of the 55 frame A, the supporting-springs, and the lubricating-rollers, mounted as shown, and operating as described.

3. The combination, in a lubricator, of the frame, the springs, and cross-head carrying 60 the oil-supply rollers, with the cams and sliding yokes or their equivalents, and oiling device, operating as set forth.

4. The combination of the frame, the supporting-springs, and oil-supplying devices 65 with the wipers for wiping off the surplus oil, substantially as described.

5. A lubricator having the base-frame, the supporting-springs, the frame carrying the rollers, said rollers having eccentrics or cams 70 or their equivalents for operating oil-supply devices, for the purpose set forth.

6. A lubricator having one or more rollers adapted to be operated by a journal, said roller or rollers being provided with eccentrics, cams, or their equivalents for operating 75 oil-supply devices.

In testimony that I claim the foregoing as my own I affix my signature in presence of two witnesses.

ADDISON BRADFORD.
